[57] CLAIM

The ornamental design for a animal litter collector, as shown and described.

DESCRIPTION

FIG. 1 is a side elevation view of an animal litter collector, showing my new design, the opposite side being a mirror image thereof;

FIG. 2 is a top plan view thereof;

FIG. 3 is a bottom plan view thereof;

FIG. 4 is a front elevational view thereof;

FIG. 5 is a rear elevational view thereof;
FIG. 6 is a front elevational view with a part thereof removed;

FIG. 7 is a side elevational view of a second embodiment;

FIG. 8 is a top plan view thereof;

FIG. 9 is a bottom plan view thereof;

FIG. 10 is a front elevational view thereof;

FIG. 11 is a rear elevational view thereof; and

FIG. 12 is a front elevational view, with a part thereof removed.

FIG. 3.

FIG. 4.

FIG. 5.

FIG. 6.

FIG. 7.

FIG. 8.

FIG. 9.

FIG. 10.

FIG. 11.

FIG. 12.
